UNITED STATES PATENT OFFICE.

FRED W. THURSTON, OF SAN FRANCISCO, CALIFORNIA, ASSIGNOR, BY MESNE ASSIGNMENTS, TO THURSTON MOTOR FUEL GASIFIER COMPANY OF CALIFORNIA, A CORPORATION OF CALIFORNIA.

HOMOGENIZER.

1,282,319.

Specification of Letters Patent. Patented Oct. 22, 1918.

Application filed September 3, 1914. Serial No. 860,033.

To all whom it may concern:

Be it known that I, FRED W. THURSTON, a citizen of the United States, and resident of San Francisco, in the county of San Francisco, State of California, have invented a certain new and useful Improvement in Homogenizer, of which the following is a specification.

This invention relates to improvements in homogenizers which are especially designed for use in connection with explosive engines where a hydrocarbon fuel of a low grade, other than gasolene, is used.

It is one of the primary objects of this invention to interpose the improved homogenizer between the carbureter and the engine so as to completely gasify not only the heavy vapor mixture from the carbureter but also to gasify the particles of fuel with which the mixture is laden when leaving the carbureter, it being understood that carburation of kerosene and other low grade oils is not possible with carbureters now in use.

It is a further object of this invention to employ a homogenizer having one or more flash heating members against which the heavy vapor is discharged so that the latter is almost instantly transformed into a dry pure gas of a high explosive efficiency.

It is a still further object to incorporate in the homogenizer a suitable means for breaking up the heavy vapor and this feature of my invention is so arranged that said means will act upon the vapor prior to its admission into the homogenizer, the homogenizing means itself being of novel construction.

Other features and objects of the invention will be more fully described in connection with the accompanying drawings, and will be more particularly pointed out in and by the appended claims.

In the drawings:

Figure 1 is a view in elevation of the homogenizer and carbureter detached from the automobile.

Fig. 2 is a longitudinal vertical sectional view of the structure shown in Fig. 1.

Fig. 3 is a sectional view on line 3—3 of

Fig. 2.

Like characters of reference designate similar parts throughout the different figures of the drawings.

The improved homogenizer, which is in-

dicated as a whole at 4, is shown connected with the exhaust manifold of an internal combustion engine (not shown) by a pipe 5, the homogenizer having an exhaust discharge 6.

Referring more particularly to Figs. 3 and 4, 7 designates an air inlet pipe into which the needle valve 8 of the carbureter extends. The carbureter includes a tank 9 into which fuel is fed or delivered from a supply pipe 10 which is connected with a fuel tank 11, as best shown in Fig. 1. A float valve limits the supply delivered to the fuel tank 9. A valve 12 is interposed in the pipe 7 to control the volume of mixture passing therethrough, and posterior to the valve 12 with respect to the direction of flow, I interpose a foraminated breaker 13 for breaking up and sub-dividing the heavy vapor and also the liquid particles of fuel carried thereby so as to facilitate transformation into gas when the mixture reaches the homogenizer, as will hereinafter more fully appear.

Reference will now be made more particularly to that part of the structure relating to the homogenizer, the function of which is to transform the heavy vapor into a gas prior to its entrance into the cylinder of the engine.

The homogenizer shown comprises a shell 14, preferably cylindrical in form, and provided with removable end caps 15 and 16, adapted to be threaded on to the shell 14, as shown. Pipe 5 delivers the exhaust gases to cap 15 and exhaust pipe 6 is connected with cap 16 to convey the discharged exhaust gases to a point below the engine, or to any other point. The shell 14 is provided with false end walls 17 and 18, which may be secured to the shell in any desired manner and which will preferably be composed of thin copper or other suitable material which is susceptible of being readily heated to a very high temperature with the least possible loss. It will be seen by reference to Fig. 3, that the false end walls or diaphragms 17 and 18 are protected against heat radiation endwise of the heater by reason of the end chambers 19 and 20, and as regards radial heat radiation, the same are protected by the overlapping margins 21 and 22 of the caps 15 and 16, which extend over the heater shell 14, inwardly beyond the diaphragms 17 and 18. The diaphragms

17 and 18 form with the shell 14 a gasifying chamber 23 through which the mixture passes on its way from the carburetor to the engine. In order to gasify the mixture, 5 the shell 14 is heated and I provide heating tubes 24 which extend through chamber 23 and which open into chambers 19 and 20 so that exhaust gases delivered by pipe 5 will pass through the tubes and outwardly 10 through discharge pipe 6. In order to render the heating action of the exhaust gases most effective against the primary or initially engaged diaphragm 17, I dispose all of the tubes 24 out of registry with pipe 5 15 so that the gases will first be directed against the diaphragm 17 and will then have to travel abreast thereof in order to reach the open intake ends of the tubes 24. Likewise, pipe 6 is out of registry with tubes 20 24 and preferably projects inwardly from cap 16, as indicated at 25, so that the gases egressing from tubes 24 will rebound from the cap 16 backwardly against and play upon diaphragm 18 prior to their discharge 25 or entrance into and through pipe 6 thereby serving to raise the temperature of diaphragm 18 almost to the same temperature as that to which the diaphragm 17, is heated, it being understood that these diaphragms 30 will be maintained at a high temperature as long as the exhaust gases are passing therethrough.

It will now be seen that the very thin diaphragms 17 and 18 operate as flash plates so 35 that the heavy vapor and any fuel particles carried thereby will be almost instantly transformed into a highly explosive gas when coming in contact therewith. The tubes 24 serve to heat the gasifying chamber 40 23 so that the high temperature of the gas will not be lost in passing through the chamber 23.

I will now describe a very important feature of my invention which consists in 45 means for conveying or causing the mixture to be directly guided against the diaphragms, and more particularly, against that portion thereof, or those portions, which attain the maximum temperature. 50 As shown, 26 designates a heater inlet pipe which is shown formed integral with shell 14 and which is connected with mixture pipe 7, at 27. By reference to Fig. 3 it will be seen that the inlet pipe 26 extends 55 a very considerable distance inside of the gasifier shell 14 so that the pipe itself will form an effective heater prior to actual admission of the mixture into the gasifier. Furthermore, pipe 26 extends toward and 60 has its terminal 28 not only in close relation with respect to diaphragm 17 but it is also disposed so that said terminal 28 will be substantially axially disposed with respect to the gasifier thereby resulting in initial 65 discharge of the mixture against the central

portion of the heated diaphragm, which will be at the highest temperature, it being understood that it is against the central portion of diaphragm 17 that the exhaust gases are discharged from pipe 5. Thus the heavy vapor 70 will almost instantly be transformed into a dry gas which will rebound from the diaphragm 17 and pass longitudinally in the gasifier toward diaphragm 18, this longitudinal passage being along the tubes 24 so 75 that the gas will not lose its heat. While the diaphragm 18 may not be as effective as the diaphragm 17, it will be sufficiently highly heated so that no loss by radiation will result. Furthermore, in practice, it is 80 found not desirable to heat the gas too highly.

An outlet pipe 29 is shown formed integral with the shell 14 and is curved like the inlet pipe 26 so that its intake terminal 85 30 will not only lie closely adjacent the diaphragm 18 but near the center thereof, which is the most highly heated portion. Outlet pipe 29 is shown connected with the intake 31 of manifold 2. 90

Now there will be a very considerable expansion in volume of the heavy vapor which has been practically perfectly gasified by diaphragm 17, and by reason of the fact that the outlet pipe 29 is not larger than the 95 inlet pipe 26, there will be a most effective play of the gas abreast of the diaphragm 18 as it seeks egress through outlet pipe 29, this being true irrespective as to whether or not the gaseous fuel flows by reason of 100 piston suction or force feed.

It is believed that the advantages and utility of my invention will be fully understood from the foregoing description, and while I have herein shown and described 105 one specific form of my invention, I do not wish to be limited thereto except for such limitations as the claims may import.

I claim:

1. In a homogenizer of the character described, a fine screen interposed in the path of the incoming gaseous fuel to break up the particles of liquid fuel carried thereby, a thin flash heating plate disposed in the path of fuel for contact thereby after the 115 fuel has passed through the screen, and means for directing a hot blast against said flash heating plate to quickly homogenize and gasify the fuel as it leaves the plate, substantially as described. 120

2. In a homogenizer of the character described, a thin flash fuel heating and homogenizing plate, means for directing a hot blast against one side of said plate and localizing the flow against one portion of the 125 plate, means for conveying off the blast and causing it to spread over said plate, and means for directing a gaseous fuel against the remaining side of said plate and localizing the flow directly opposite the point of 130

localization of flow of the blast and causing the fuel to spread over said plate, substantially as described.

3. In a homogenizer, in combination, a heater, a thin flash heating diaphragm at each end of said heater, means for causing exhaust engine gases to pass through said heater from one diaphragm to the other and heat said diaphragms, means for discharging a fuel mixture against one of said diaphragms, and means for discharging the said fuel mixture, after heating, from a point directly abreast of the other of said diaphragms, substantially as described.

15 4. In a homogenizer, in combination, a heater, a thin flash heating diaphragm at each end of said heater, means for passing waste gases into contact with one side of each diaphragm, means for protecting said diaphragm from radiation, means for conducting said waste gases from one diaphragm to the other, and means for discharging a fuel admixture directly against one of said diaphragms, and means for taking it 25 away from directly abreast of the other of said diaphragms, substantially as described.

5. For homogenizing a fuel admixture, in combination, a heater, a thin flash heating diaphragm at each end of said heater, open

ended heating tubes connecting said diaphragm through said heater and being fixed radially from central portions of said diaphragms to cause the waste gases to spread after initial contact with said diaphragms, a cap over each end of the heater, said caps forming chambers between each cap and its respective or adjacent diaphragm, a pipe leading to one of said chambers to deliver waste gases centrally of one of said diaphragms and the other of said chambers having a discharge opening for the exhaust gases, a fuel pipe discharging in said heater directly against one of said diaphragms, and a fuel pipe arranged to take off the fuel from a point directly abreast of the other of said diaphragms whereby fuel laden air is caused to absorb the heat from each of said diaphragms and from said heating tubes, to vaporize and unvaporized fuel, substantially as described.

30 35 40 45 50 In testimony that I claim the foregoing as my own, I hereby affix my signature in the presence of two subscribing witnesses.

FRED W. THURSTON.
